UNITED STATES PATENT OFFICE.

GEORGE U. TOMPERS, OF BROOKLYN, NEW YORK.

SYRINGE-HOLDER.

1,202,245.

Specification of Letters Patent.

Patented Oct. 24, 1916.

Application filed February 15, 1915, Serial No. 8,350. Renewed March 25, 1916. Serial No. 86,801.

To all whom it may concern:

Be it known that I, GEORGE U. TOMPERS, a citizen of the United States of America, and resident of the borough of Brooklyn, county of Kings, and State of New York, have invented certain new and useful Improvements in Syringe-Holders, of which the following is a specification.

This invention relates to improvements in 10 syringe holders, and more particularly to that class of holders which may be used either for external appliance, as with an ordinary hot water bottle, or as a syringe-reservoir for vaginal, rectal, enema or other 15 such applications.

An object of the present invention is to provide such a device which may be more effectively and conveniently operated than in previous constructions, which will permit a 20 comfortable and natural use of the same, and enable a greater or less pressure to be given to the liquid, as desired.

Another object is to provide such a device which may be readily used for external 25 applications, of such a shape that it will conform to various portions of the body.

With these and other objects in view, my 30 invention consists of the novel features, arrangement and construction of parts, hereinafter more fully described and pointed out in the claims.

In the drawings, Figure 1 is a perspective view of my improved holder; Fig. 2 is an 35 end view of the same; Fig. 3 is a sectional view thereof; Fig. 4 is a sectional view showing a slightly modified form; Fig. 5 is a 40 section of my holder used as an air-cushion, with syringe attachment; Fig. 6 is a section of a slightly modified form used as an air-cushion; and, Fig. 7 is a detail showing the 45 nozzle connection.

Similar reference characters indicate corresponding parts throughout the several 50 views.

Referring to the drawings, and more particularly to Figs. 1 and 3 thereof, a circular or other suitably shaped receptacle 1 of rubber, having a central opening 2 therethrough, and a rubber disk 3 secured to its top, is provided 55 at one end with a filling passage 4, into which a stopper 5 is screwed, and at its other end with an outlet opening 6 and rubber tube 7. The said rubber disk 3 is provided centrally with an aperture 8, and a portion of the same opposite the outlet end of the holder is left unsecured, as at 9, to form a flap

under which the end of the rubber tube 7 passes, and is connected to the nippled end of a pipe 10. The said pipe 10 is secured to a water chamber 11, which is secured to a 60 rubber nozzle 12 through the aperture 8 by means of a threaded projection 13 and recess 14 on the chamber and nozzle respectively. The threaded portion of the nozzle is preferably of metal as shown in Fig. 7. It will be 65 seen that when filled, as shown in Fig. 3, any pressure on the top of the holder, caused by the weight of the person using the same, will force the water through the tube and out of the nozzle. The force of the water through 70 the nozzle may be regulated as desired according to the pressure exerted on the holder.

In the form shown in Fig. 4, an outlet opening is dispensed with, and the end of the rubber tube 7 is provided with a threaded nipple 15 of metal, hard rubber, or the like, which is screwed into the filling opening after the receptacle is filled.

In Fig. 5 I have illustrated a form where-in the receptacle is filled with air, through a valve 16, to form a cushion, and the pipe 10 is supplied with water through a tube 17 connected to a suitable receptacle at a higher level (not shown). A slightly modified form of this last construction is shown in Fig. 6, 85 wherein the top rubber disk is dispensed with and the receptacle is provided with a central web 18 having an aperture 19 through which the nozzle is attached to the pipe 10. The holder in this form is preferably corrugated, as at 20, for passage of the tube under the same.

When it is desired to use the holder for external application, the nozzle 12, water tube 7, and pipe 10 are removed and the outlet opening 6 is closed, whereupon the holder is filled with water and the stopper 5 placed in the filling opening 4. In this way a most conveniently shaped hot water bottle is provided.

In the embodiments, the web has an aperture with the nozzle at one side of the web and perpendicular thereto, and with a pipe at the other side of the web and connected through the aperture with the nozzle and perpendicular thereto and parallel with the web. The nozzle, in the preferred form, has a base portion, the base of which, as is shown in the drawings, is flat, and which contacts at all portions thereof with one side 105 of the web. In this form, the pipe has an enlarged portion having a flat portion con-

tacting at all its portions with the underside of the web and at points immediately below the flat part of the base portion of the nozzle.

5 I have illustrated and described preferred and satisfactory forms of my invention, but it is obvious that changes may be made therein without departing from the spirit and scope thereof, as defined in the 10 appended claims.

I claim:

15 1. A device of the character described, comprising a web having an aperture, a nozzle on one side of the web and perpendicular thereto, and a pipe at the other side of the web and connected through said aperture with the nozzle and perpendicular thereto and parallel with the web, and extending from the nozzle along the underside of the web, said pipe being rigid and rigidly connected with the nozzle.

20 2. A device of the character described, comprising a web having an aperture, a nozzle at one side of the web and perpendicular thereto, a pipe on the other side of the web and perpendicular to the nozzle and parallel with the web, and connected through said aperture with the nozzle and extending along the underside of the web, and a cushioning member for said web and secured thereto at the edges of the web.

25 3. A device of the character described, comprising a web having an aperture, a nozzle at one side of the web and perpendicular thereto, a base portion for said nozzle, the base of which is flat and which contacts at all portions thereof with one side of the web, a pipe at the other side of the web and connected through said aperture with the nozzle and perpendicular thereto, and parallel with the web, and extending from the nozzle 40 along the other side of the web contiguously

thereto, and an enlarged portion for said pipe having a flat portion contacting at all its portions with the underside of the web, 45 and at points immediately below the flat part of the base portion of the nozzle.

4. A device of the character described, comprising a web having an aperture, a nozzle at one side of the web and perpendicular thereto, a base portion for said nozzle, the base of which is flat and which contacts at all portions thereof with one side of the web, a pipe at the other side of the web and connected through said aperture with the nozzle and perpendicular thereto and parallel with the web, and extending from the nozzle along the other side of the web contiguously thereto, an enlarged portion for said pipe having a flat portion contacting at all its 55 portions with the underside of the web and at points immediately below the flat part of the base portion of the nozzle, and a cushioning member for said web and secured thereto at the edges of the web.

5. A device of the character described, comprising a web having an aperture, a nozzle on one side of the web and perpendicular thereto, and a pipe at the other side of the web, and connected with the channel of the nozzle, and arranged entirely beneath the web, and extending from the nozzle along the underside of the web, the web being adapted to support the nozzle in operative position while being supplied with 70 fluid fed through the pipe.

In testimony that I claim the foregoing as my invention, I have signed my name in presence of two subscribing witnesses.

GEO. U. TOMPERS.
